UNITED STATES PATENT OFFICE.

HENRY BARKSCHAT, OF LOS ANGELES, CALIFORNIA, ASSIGNOR TO MARBELITE CORPORATION OF AMERICA, OF LOS ANGELES, CALIFORNIA, A CORPORATION OF DELAWARE.

DESIGN FOR A COMBINATION POST AND LIGHTING STANDARD.

Application filed February 6, 1926. Serial No. 16,431. Term of patent 14 years.

To all whom it may concern:

Be it known that I, HENRY BARKSCHAT, a citizen of the United States, residing at Los Angeles, in the county of Los Angeles, State of California, have invented a new, original, and ornamental Design for a Combination Post and Lighting Standard, of which the following is a specification, reference being had to the accompanying drawing, forming a part thereof.

The figure is an elevation of a combination post and lighting standard showing my new design.

I claim:

The ornamental design for a combination post and lighting standard, as shown.

HENRY BARKSCHAT.
